UNITED STATES PATENT OFFICE

HERBERT C. HERING, OF CINCINNATI, OHIO

CURTAIN DISPLAY HANGER

Application filed October 22, 1931. Serial No. 570,470.

The present invention relates to the art of curtain and drapery displaying, and is more especially concerned with a novel and improved method and means particularly adapted for use by manufacturers and wholesalers of curtains, or their traveling salesmen, for expeditiously and effectively displaying their wares. More specifically, the present invention has particular relation to a new and improved construction of curtain display hanger.

The common present-day practice in the displaying of curtains to buyers by manufacturers and wholesalers of curtains in their show rooms and on the road involves a great deal of tedious and expensive time-consuming labor. In addition, the usual practice does not permit of exhibiting the curtain or drapery wares in a manner to obtain an effective display thereof. The curtains are generally folded to occupy an area which is a small fraction of that of the unfolded curtain.

Thus, a curtain which may measure 30"×40" is folded until its dimensions are approximately 8"×13", and this usually involves a minimum of four folds. A curtain sample line of a manufacturer may run from 50 to 1000 or more samples, and the latter are usually arranged on a table or tables in stacks of folded samples sorted according to price, each stack containing from 5 to 20 or more samples. It is obvious that the folding of the curtains is necessary in order to enable the entire line to be accommodated on the generally available table surface.

When the buyer is shown the samples, each curtain has to be unfolded and displayed manually in order that the buyer may properly view the goods and make his selections. After the buyer has gone, the samples must again be folded and sorted into proper stacks before they may be displayed to the next buyer. This clearly is greatly time-consuming and expensive because with a fairly extensive line only one or perhaps two buyers may be interviewed in the course of a day.

The primary object of the present invention

accordingly is to enable curtain and drapery material sample lines to be shown to buyers in a better, quicker and more effective manner than was heretofore possible, and to eliminate for the manufacturer or wholesaler the necessity of continually folding and unfolding the curtain or drapery material samples. 55

Another object of this invention is the provision of a new and improved display hanger 60 particularly adapted for use in the exhibition of curtain and drapery samples, and which shall attain the objects outlined in the preceding paragraph.

A further object of the invention resides 65 in the provision of a display hanger, as above described, which shall be relatively simple and inexpensive in construction, light in weight, and easily handled.

Still another object of the present invention is to provide means for exhibiting curtain and drapery samples to the trade without the necessity of folding them or stacking them on tables or the like, and without involving any change whatever in the 75 usual construction of the samples.

The foregoing and other objects which will be apparent to those skilled in the art to which the present invention pertains from the detailed description thereof hereinafter given, are attained by the illustrative embodiments of the invention herein disclosed, consisting of the novel combination and arrangement of parts fully described below, illustrated on the accompanying sheets of 85 drawings, and particularly pointed out in the claims hereunto appended.

On the said sheets of drawings,

Fig. 1 shows a curtain and display hanger therefor disposed in operative relationship according to the present invention; 90

Fig. 2 is a front view of the ends of the hanger rod, the central portion thereof being broken away;

Fig. 3 is a sectional view through the 95 hanger rod, taken on line 3—3 of Fig. 2;

Fig. 4 is a front view of the central portion of the hanger rod with one form of clip hook mounted thereon, the curtain being omitted for the sake of clearness; 100

Fig. 5 is an end view of the construction illustrated in Fig. 4;

Fig. 6 is a view corresponding to that of Fig. 4, but showing a modified construction 5 of clip hook;

Fig. 7 is an end view of the construction illustrated in Fig. 6.

Similar reference numerals designate corresponding parts throughout the several figures of drawings.

Referring to the drawings, and more particularly at first to Fig. 1 thereof, reference numeral 10 designates a conventional form of curtain comprising a heading 11, a rod 15 casing 12, valance 13, and ruffle 14. Rod casing 12 is adapted to encase the hanger rod 15 of the display hanger, according to the invention.

Hanger rod 15 is preferably of such 20 length as will properly support curtain sample 10 in the same manner as a curtain rod, and it may consist of a length of wood strip, desirably of the cross section particularly illustrated in Figs. 3, 5 and 7. For 25 this purpose, if desired, use may be made of window shade slats. It will be understood, however, that the shape of the hanger rod as well as the material of which it is made may be changed as deemed expedient. The 30 rod, for instance, may be made of a light weight metal if desired.

Securely mounted on each end of hanger rod 15 is a curtaining ferrule or end clip 16 which securely encompasses its respective 35 end (see Figs. 2 and 3), and which is held in place by conventional attaching means, such as a screw or brad 17. Extending inwardly of each ferrule or clip 16 and on each 40 side of hanger rod 15 is an outwardly bowed spring arm 18. As may clearly be seen from Fig. 1 of the drawings, these spring arms 18 operate to securely retain the edges of curtain 10 in proper position on the hanger rod and prevent displacement thereof. Ferrules or clips 16 and their spring arms 18 45 may conveniently be constructed of steel.

According to the present invention, each curtain sample is mounted on a hanger rod after the manner heretofore described, and 50 the several samples are suspended, so that they may be quickly and effectively displayed, from rods or extended arms somewhat after the fashion of clothes hangers.

Means is accordingly provided for suspending each curtain and rod, and one form 55 of such means is illustrated in detail in Figs. 4 and 5. This form preferably comprises a clip-hook, the clip portion 19 of which is fabricated from a single strip of 60 suitable metal. This strip is bent intermediate its ends to form a springy loop 20 from which a pair of arms 21 extend.

Adjacent the lower ends of arms 21, they 65 are deformed in shape so that the space between the deformations corresponds to the

cross section of rod 15 (see Fig. 5). Arms 21 are bent outwardly at the lower ends thereof to form guides 23 to enable the clip-hook to be more easily slipped into place. As a result of the springy character of clip 70 19, the arms 21 thereof are constantly urged toward each other.

An important feature of the construction of clip 19 is that the portion of arms 21 thereof above deformations 22 is of such 75 length that curtain heading 11 is easily disposable therebetween without crushing the curtain which might spoil the appearance thereof. The clip is bent in such manner that when it is slipped onto rod 15, arms 21 are in substantially parallel relationship to each other (Fig. 5), and the heading 11 is adapted to be arranged therebetween.

The hook portion 24 of the clip-hook consists of a hook-shaped metal rod 25, the 80 lower part 26 of which, to an extent substantially equal in length to the width of strip 19, is bent laterally and extended through loop 20. End 27 of hook 25 is bent upwardly, as shown, to prevent relative disengagement of the parts. Part 26 is not straight but is preferably bent to form a very shallow V, for a purpose hereinafter described. The diameter of rod 25 is proportioned so that it is greater than the space 85 between arms 21, retaining part 26 in place in loop 20.

It is to be noted that a hanger rod provided with a permanent hook is not feasible in a device of this character because the 100 size of the conventional rod casing is too small to permit rod and hook to pass therethrough. Furthermore, the curtain would have to be made with an opening for the hook, and this would be objectionable. According to the present invention these deficiencies are obviated, and a conventional curtain sample may be used.

Hook-clip 19, 24 is slipped over rod 15 and curtain 10 to the position shown in Fig. 1, by bending the hook 24 half way toward the operator thereof. The V cam 28 spreads the spring clip sufficiently to permit the same to be easily slipped over the rod and curtain. After the clip is in place, the hook 24 is returned to its normal position, and the tension exerted by the spring clip 19 will retain it firmly in place. The clip is removed in a similar manner.

In Figs. 6 and 7, a second form of hook-clip is illustrated. This comprises a pair of pivotally connected arms 21', formed with deformations 22' and guides 23', which correspond to members 21, 22, and 23 of the preferred form previously described. Hook 24' is permanently secured to one of arms 21', and the latter may be reinforced, if desired, by strengthening ribs 29. A spiral spring 30, disposed about pivot pin 31, urges arms 21' toward each other. It is to be 130

noted that the space between the hinge portion of the device and the top of deformations 22' is of an extent adapted to receive the heading 11 of a curtain sample without 5 crushing.

Although two exemplary embodiments of the invention have been described in some detail, it is not thereby intended to limit the scope of the invention, nor otherwise than 10 by the terms of the appended claims.

What is claimed is:

1. A hook-clip for use in a curtain display hanger comprising a clip portion made from a single strip of metal bent intermediate its ends to form a spring loop, and a hook portion extending from said loop and retained against displacement therefrom. 15

2. A hook-clip of the character described comprising a pair of rod-encompassing arms, 20 a spring loop connecting said arms at one end thereof and urging them toward each other, a hook partially encased by and extending from said loop, and means on said hook for separating said arms against the 25 action of said spring loop.

3. In a curtain display hanger, a hanger rod adapted to be received in the rod casing of a curtain to be displayed, means on said rod for retaining said curtain in position 30 thereon, and a hook-clip for suspending said rod from a support with a portion of said curtain disposed between said rod and hook-clip, said hook-clip comprising a portion adapted to substantially encompass said rod 35 and a second portion adapted to receive part of the heading of said curtain in uncrushed form. 40

4. A curtain rod hook-clip for use in displaying a curtain including a rod casing 45 and a heading and mounted on a curtain rod, said hook-clip comprising a clip adapted to substantially encompass said casing and rod intermediate the ends of the latter, said clip comprising a casing-and-rod-encompassing portion, spring means for tensioning said encompassing portion against said casing and rod, and spaced elongated portions between the first-named portion and said spring means adapted to receive said curtain heading 50 therebetween, whereby said heading may be displayed in uncrushed condition. 55

5. A hook-clip of the character described comprising a metallic clip portion including a springy loop intermediate the ends thereof, and a hook portion mounted on said clip portion and retained against displacement therefrom, said hook portion including a cam surface disposed within said loop. 60

6. The construction defined in claim 2, 65 said means comprising a substantially V-shaped cam.

7. A hook-clip of the character described comprising a metallic clip portion including a springy connection intermediate the ends thereof, and a hook portion mounted on said

clip portion and retained against displacement therefrom, the ends of said clip portion being adapted to substantially encompass a coacting curtain rod and intermediate sections of said clip portion being spaced apart 70 and adapted to receive in uncrushed form a part of the heading of a curtain which is mounted on said rod.

In testimony whereof I affix my signature. 75
HERBERT C. HERING.
